UNITED STATES PATENT OFFICE.

JAY O. WOODS, OF RIVERSIDE, WASHINGTON, ASSIGNOR OF ONE-HALF TO JOSEPH W. GRAHAM, OF RIVERSIDE, WASHINGTON.

THERMOSTATIC CIRCUIT-CLOSER.

No. 884,969.

Specification of Letters Patent.

Patented April 14, 1908.

Original application filed October 5, 1906, Serial No. 337,585. Divided and this application filed May 10, 1907. Serial No. 372,932.

To all whom it may concern:

Be it known that I, JAY O. WOODS, a citizen of the United States, and a resident of Riverside, in the county of Okanogan and 5 State of Washington, have invented certain new and useful Improvements in Thermostatic Circuit-Closers, of which the following is a specification.

My invention relates to improvements in 10 thermostatic circuit closers and is designed to be used in connection with incubators particularly with the construction shown and described in a pending application Serial No. 337,585, filed by the present applicant, being 15 a division of said pending application.

The object of the present invention is to produce a circuit closing device which will positively act to regulate the heat in an incubator by actuating a damper.

20 With these objects in view my present invention consists in certain novel features of construction, arrangement and combination of parts as will be hereinafter fully described and pointed out in the claims, reference being 25 had to the accompanying drawing in which

Figure 1 is an elevation of my improved thermostat, Fig. 2 is a sectional view of my incubator showing application of my thermostat, Fig. 3 is an enlarged sectional view of 30 the thermostat.

In carrying out my invention I use my thermostat in connection with my improved incubator illustrated in Fig. 2 of the drawing. The thermostat consists of a glass tube 14 having the bulbs 14^a and 14^b at its upper and lower ends respectively; within this tube the column of mercury 15 is placed, and resting on the mercury is the rod 16 consisting of a pin or rod of hard rubber or gutta-percha; 35 the upper end or head of the hard rubber rod 16 is enlarged and provided with a tip 17 made of copper, aluminium or any other suitable conducting material which is beveled to a point and has the appearance of an arrow head; this tip may be a solid piece of the material used, or the upper end of the rod 16 may be beveled to a point and a piece of conducting material bent over it and secured there. Extending into the upper bulb of the 40 thermostat are the wires or electrodes 18 and 19 which pass up through the egg chamber of the incubator and then out of same, one (18) passing to one pole of the battery 20 and the other (19) after passing through the electro-

magnet 21 passes to and connects with the 55 opposite pole of the battery. The electro-magnet controls an armature 22 which controls the damper 23 through the connecting rod 24 as shown in Fig. 2.

Normally the tip 17 will be below and out 60 of contact with the ends of the wires 18 and 19; if now the heat in egg chamber, (or wherever the thermostat is used) rises above the predetermined degree the mercury lifts the float rod until the beveled tip 17 comes in 65 contact with the wires 18 and 19 and forms a bridge between the two, closing the circuit through the electro-magnet and battery; the armature 22 being attracted by the electro-magnet moves inwardly and causes the damper to swing to a vertical position shutting off 70 heat from the lamp the heat then passing straight up and into the open air. Thus the heat is shut off instantly as soon as the temperature in the egg chamber gets above the 75 predetermined point, and as soon as the temperature of the egg chamber has lowered sufficient to cause the mercury to fall and allow the hard rubber to drop and draw the conductive tip away from the wires 18 and 80 19, the circuit will be broken and the damper will be swung to its inclined position permitting the heat of the lamp to again pass to the hot air duct 25.

By using the hard rubber rod having the 85 conductive tip, the heat of current will not heat the mercury, as if the mercury is heated, the circuit would be held closed much longer than is desired and would then allow the temperature of the egg chamber to 90 fall too low.

With my improved construction the circuit is instantly closed when the heat goes beyond the predetermined degree, and is instantly opened when it again reaches said 95 predetermined degree, and furthermore no heating of the mercury can take place from the heat of the electric current as said current passes through the copper tip and is completely insulated and isolated from the 100 mercury column by the hard rubber rod.

It will thus be seen that I produce a simple, cheap and efficient thermostatic circuit closer, which is extremely delicate, sensitive and positive in its action.

What I claim is:

1. A thermostatic circuit closer consisting of a thermometer tube hermetically sealed at

its upper and lower ends and containing a mercurial column, two wires forming the terminal contacts of an open circuit and entering the thermometer above the mercury column, a rod of insulating material adapted to be lifted by said mercurial column the upper end of said float provided with conducting material, whereby expansion of the mercury above a predetermined degree will cause the rod to bridge the ends of the terminal wires of the open circuit and close the circuit.

2. A thermostatic circuit closer comprising a tube hermetically sealed at its upper and lower ends and having a central bore terminating at its lower end in a mercury bulb and at its upper end in an enlarged chamber in which are arranged out of contact with each other the terminals of an open electric circuit, a rod of insulating material adapted to be lifted by the column of mercury in the tube, said rod having at its upper end conducting material to bridge the space between the ends of the terminal wires and close the circuit.

3. A thermostatic circuit closer comprising a tube hermetically sealed at its upper and lower ends and having a central bore terminating at its lower end in a mercury bulb and having a space above the mercury column, a pair of terminal wires forming part of an open circuit and projecting into the space above the mercury, a slidable rod

of insulating material adapted to be lifted by said column of mercury, said rod having its upper end pointed and covered with a conducting material to bridge the space between the ends of the terminal wires and close the circuit.

4. A thermostatic circuit closer consisting of a tube hermetically sealed at its upper and lower ends and having enlarged bulbs at said upper and lower ends, and a reduced central bore, a pair of terminal wires forming part of an open electric circuit and projecting into the upper bulb, the ends of said terminals being spaced apart, a slidable rod of insulating material having a body portion adapted to fit loosely in the bore of said tube and an enlarged head projecting into the upper bulb, said head being of greater diameter than that of the central bore of the tube, said head portion having beveled sides covered with a conducting material, whereby when the rod of insulating material is lifted by the expansion of the column of mercury within the tube, the space between the ends of the terminal wires will be bridged and the open circuit closed.
